United States Patent

Des. 235,629
Patented July 1, 1975

235,629

OPTICAL SMOKE DETECTOR

Donald F. Steele, River Road, Cohasset, Mass. 02025,
and Hugh P. Thornton, Jr., Kelly Road, Acton, Mass.
01720

Filed Sept. 28, 1973, Ser. No. 401,941

Term of patent 14 years

Int. Cl. D29—02

U.S. Cl. D10—106

FIG. 1

FIG. 2

FIG. 3

FIG. 1 is an isometric view from one side of the optical smoke detector showing our new design;

FIG. 2 is an isometric view from the opposite side of the detector on approximately half the scale of FIG. 1; and

FIG. 3 is an elevation of the detector on a scale slightly larger than FIG. 1.

We claim:

The ornamental design for an optical smoke detector, as shown and described.
